[57] CLAIM

The ornamental design for a tank for pharmaceutical manufacturing processing, as shown.

DESCRIPTION

FIG. 1 is a front elevational view of a tank for pharmaceutical manufacturing processing showing my new design;

FIG. 2 is a left side elevational view thereof;

FIG. 3 is a right side elevational view thereof;

FIG. 4 is a bottom plan view thereof;

FIG. 5 is a top plan view thereof;

FIG. 6 is a back elevational view thereof; and

FIG. 7 is a perspective view which shows the tank is

placed on a cart.
The broken line showing of a cart in FIG. 7 is for illustrative purposes and forms no part of the claimed design.
